United States Patent Office.

ROBERT T. MOSS, OF CAMBRIDGE, OHIO.

Letters Patent No. 70,105, dated October 22, 1867.

IMPROVED BUCKLE-ATTACHMENT.

The Schedule referred to in these Letters Patent and making part of the same.

TO ALL WHOM IT MAY CONCERN:

Be it known that I, ROBERT T. Moss, of Cambridge, in the county of Guernsey, and in the State of Ohio, have invented certain new and useful improvements in Mode of Attaching Buckles and Rings to Harness; and do hereby declare that the following is a full, clear, and exact description thereof, reference being had to the accompanying drawings, and to the letters of reference marked thereon.

The nature of my invention consists in the use of sheet-metal plates, provided with suitable slots for receiving the tongues of buckles, and with holes through which said plates may be riveted to the leather strap to which it is desired to connect the buckle; and further, in the general use of metal plates, which are adapted by their formation and structure to the connecting of rings and buckles to leather straps.

In the drawings A A represent the metallic plates. These plates may be made in a variety of forms, according to the uses for which they may be designed. In Figures 5 and 6 the plates are represented with slots or openings C C, for the tongue of the buckle. After the tongue is inserted the plates are bent down, so that their two ends embrace the leather strap to be confined, and rivets are then inserted through the plates and through the leather, confining the two firmly together. In fig. 5 the plate is cut with wings at one end, which bend over on a line from x to x', embracing the opposite end of the plate. B B represent the buckles. In fig. 2 a plate is represented, a plate bent over the two ends of a keeper, for the purpose of confining said keeper to the strap.

Having thus fully described my invention, what I claim as new, and desire to secure by Letters Patent, is—

The slotted metal plates A A, constructed as described, for attaching buckles to the ends or sides of straps, and shielding the edges of the leather, as set forth.

In testimony that I claim the foregoing I have hereunto set my hand this 6th day of June, 1867.

ROBERT T. MOSS.
